UNITED STATES PATENT OFFICE.

MICHAEL LUNNEY, OF CHELSEA, MASSACHUSETTS.

SINK-TRAP CLEANER.

1,085,052.

Specification of Letters Patent.

Patented Jan. 30, 1914.

Application filed July 22, 1913. Serial No. 780,807.

To all whom it may concern:

Be it known that I, MICHAEL LUNNEY, a citizen of the United States, residing at Chelsea, in the county of Suffolk and State of Massachusetts, have invented new and useful Improvements in Sink-Trap Cleaners, of which the following is a specification.

My invention relates to improvements in sink trap cleaners, and one of its objects is the provision of a device of this character which will permit the effective cleaning of a sink trap from the usual source of water supply.

A further object of the invention is the provision of a sink trap cleaner which shall be simple, durable, and efficient and which may be manufactured and sold at a comparatively low cost.

With the above and other objects in view the invention consists in the construction, combination, and arrangement of parts hereinafter fully described and claimed, and as shown in the accompanying drawing, wherein the figure of the drawing is a sectional view illustrating the use of my improved sink trap cleaner.

Referring to the drawing by reference numerals, 1 designates the hollow rigid body of the cleaner. The body 1 comprises a substantially cylindrical portion 2, and a substantially frusto-spherical portion 3, the portions 2 and 3 being preferably formed integral. At its lower edge the body 1 is provided with a horizontally disposed and inwardly extending flange 4 which may be formed integral with the body in any suitable manner. The flange 4 is annular so as to provide the body 1 with a discharge opening 4^a, which has a diameter a little greater than the diameter of the screen 5 of the sink trap 6. To establish a water tight connection between the body and the bottom 7 of the sink 6 about the screen 5, a gasket 8 of rubber or other suitable material is secured to the under side of the flange 4. As shown at 9 the inner edge of the flange 4 may be provided with a downwardly and outwardly extending roll flange for the reception of the inner periphery of the gasket 8 to secure it in applied position. Any other suitable means such as cement or other adhesive may be employed to secure the gasket to the flange.

The uppermost portion of the frusto-spherical portion 3 of the body 1 is provided with an opening 10 which is smaller

than and arranged concentric with relation to the opening 4^a. A member which comprises a nozzle 11 and a coupling 12 passes through the opening 10, the nozzle 11 being wholly within and the coupling 12 wholly without the body 1. The combined nozzle and coupling member may be secured to the body 1 in any suitable manner, as for instance, by solder as shown at 13. A hose section 14 provided with couplings 15 and 16 is used in connection with body 1. One end of the hose is connected to the sink faucet 17 by means of the coupling 16, and the other end of the hose is connected with the coupling 12 by means of the coupling 15.

The manner in which my improved sink trap cleaner is adapted to be used may be stated to be as follows: After the hose 14 is connected to the coupling 12 and the faucet 17, the body 1 is placed over the strainer 5 of the sink trap 6. The water supply is then turned on and the body is held in place by the hand. The discharge end of the nozzle 11 is reduced, and owing thereto and to the fact that the nozzle projects into the body 1, the back pressure of water within the body acts against the curved inner wall of the frusto-spherical portion 3 of the body and not against the head of water entering the body, this allows a large quantity of water to accumulate within the body and when the stoppage within the trap begins to break away this supply of water will rush down through the trap and quickly and effectively flush it out whereby the entire amount of the water is utilized to effect the cleaning of the trap 6. The gasket 8 establishes a water-tight connection between the lower end of the body 1 and the bottom wall 7 of the sink about the entrance to the trap 6.

From the foregoing description taken in connection with the accompanying drawings the construction and mode of operation of the invention will be understood without a further extended description, changes in the form proportions and minor details of construction may be made within the scope of the invention without departing from the spirit or sacrificing any of the advantages thereof.

What I claim is:

A sink cleaner comprising a hollow rigid body having a comparatively high cylindrical lower portion and a frusto-spherical up-

per portion, said portions being formed integral, a horizontally disposed and inwardly extending annular flange formed on the lower edge of a cylindrical body portion, a downwardly and outwardly extending roll flange formed on the inner edge of the said annular flange, an annular gasket arranged on the under side of the said annular flange and having its inner periphery secured in the recess formed by the roll flange, a small opening provided in the uppermost portion of the frusto-spherical body, said opening being arranged concentric with the large opening located within the inner periphery of the said annular

flange, a combined coupling and nozzle arranged in the said small opening and rigidly secured therein, the said coupling being located wholly without the said body and provided with a threaded extremity, said nozzle being located wholly within the said frusto-spherical body and being internally and externally tapered, and means to supply water to the body.

In testimony whereof I affix my signature 25
in presence of two witnesses.

MICHAEL LUNNEY.
